UNITED STATES PATENT OFFICE

ROBERT SCHITTKO, OF LANSING, MICHIGAN

OIL COOLING SYSTEM

Application filed March 31, 1930. Serial No. 440,384.

This invention relates primarily to a novel oil cooling and engine cooling organization; but it also includes various novel sub-combinations. For example, it is an object of 5 the invention to operate an oil pump by a direct and co-axial forward extension of a camshaft, said pump being preferably carried in an external and accessible position adjacent an oil cooler,—as, by a housing 10 which extends over a sprocket gear employed in the driving of said camshaft; and the invention preferably includes novel means for feeding or priming said pump from a conduit containing lubricant under pressure, 15 —such as a conduit extending longitudinally of said shaft and included in a gravity or pressure oil feed system.

It is also an object of this invention to provide for the direct operation of a water 20 pump from a fan shaft,—the rotor of said pump, when of centrifugal type, being carried by said shaft; and, in preferred embodiments of the invention, in order that the 25 pumped water may advance through an oil cooler disposed therebelow, a bifurcate or other cooler outlet fitting may serve as a bracket for the support of not only said cooler but said water pump and said fan shaft.

30 It is an object of this invention to provide an oil cooler one of whose water headers is integral with a pump chamber (said chamber preferably carrying a bearing for a fan shaft) and the other of whose headers is 35 integral with a fitting which serves not only to provide for the exit of cooling fluid but for the support of said cooler and parts thereabove. Said cooler is preferably similar in type to the Ramsaur-Chase cooler (described 40 and claimed in application S. N. 407,730 filed Nov. 16, 1929) in that it includes a set of tubes having "hex" ends through which water may descend while the oil to be cooled is advanced transversely therebetween; and, 45 in one advantageous embodiment, the cooled lubricating fluid may be permitted to descend into a pan in proximity to the intake of an additional pump,—the latter being ordinarily included in a pressure-feed or serv- 50 ice circuit which supplies various bearings

and which includes a mentioned conduit from which the pump of the cooling circuit is primed.

Other objects of the present invention, including the positioning of a cooler and pumps favorably to direct cooling, may be best appreciated from the following description of an illustrative embodiment thereof, taken in connection with the appended claims and the accompanying drawings:

Figure 1 is a diagrammatic side elevational view showing an internal combustion engine in which one embodiment of the present invention is incorporated.

Figure 2 is a vertical section corresponding to a left central portion of Figure 1.

Figure 3 is a front elevational view, with parts sectioned substantially as suggested by a line 3—3 of Figure 2.

Figure 4 is a horizontal sectional view, 70 taken substantially as suggested by the broken line 4—4 of Figure 3.

Referring to that embodiment of the present invention which has been selected for purposes of illustration, an engine block 11 75 is shown as having secured therebelow an oil pan 12 and as comprising (along with numerous usual parts) a camshaft 13, driven (through a sprocket chain, of usual type) by a terminally secured gear 14,—the latter being enclosed within a housing 15. At the front of the block 11, there is shown a fan F to advance air for a cooling effect, a radiator R being shown in front thereof.

Coming now to novel features of the present invention, the block 11 is shown carrying, at the front thereof, an oil pump O. P., an oil cooler O. C., and a water pump W. P. Camshaft 13 is shown as carrying, by means of screws 16 (which serve also to retain the gear 14) a plate 17, having a non-circular central opening at 18,—the parts last referred to being employed to transmit rotation to an extension shaft 19, terminally interfitting within said opening. The shaft 19 is shown as extending through a bearing 20, provided upon the housing 15, and as adapted to impart movement to a rotor in the form of a gear 21,—cooperating with a companion gear 22 and housed within a concave and fixed ele- 100

ment 23, serving as an oil pump chamber. This chamber may be secured to the housing 15 by means such as screws 24; it may be provided with an oil inlet at 25 and with an oil 5 outlet at 26; and, if desired, resilient means such as a compression spring 27, within a bearing thimble 28, may cooperate with an outer terminal bearing plate 29 in normally maintaining the shaft extension 19 in the 10 illustrated relation to camshaft 13.

The camshaft 13 is shown as provided with a central and longitudinally extending conduit 30, which may be included in a pressure lubricating system; and, in order to assure 15 the presence of sufficient lubricant for a priming effect in an oil pump located and constructed in the described manner, not only the mentioned thimble 28, the mentioned extension shaft 19 and the bearing plate 29, but 20 also any additional interposed element such as a washer 31, serving as an abutment for spring 27, may be provided with openings, as at 32, 33, 34 and 35, co-axial with the mentioned conduit 30 and communicating, by an 25 inclined passage 36, with the interior of the oil pump chamber provided by the concave element 23, or its equivalent.

It will be obvious that means of the described character might be employed to pump 30 oil into any suitable pressure reservoir or elevated container, permitting direct or indirect flow into a pressure or gravity system, or other lubricating system, including the mentioned conduit 30; but the oil pump outlet 35 26 is herein shown as connected, by a pipe 37, with the oil cooler O. C.; and this oil cooler preferably includes not only oil headers (which may be comprised in a main casting 39, with which an oil inlet fitting 40 and 40 an oil outlet fitting 41 may communicate) but also a water inlet header element 42 and and a water outlet header element 43,—the latter being shown as a downwardly bifurcate bracket which is integral with water delivery 45 fittings 44, 44', provided with means for their direct attachment to the engine block 11, opposite openings into the jacket thereof.

Between the main casting 39 and the respective water headers 42 and 43, there may 50 be interposed horizontally extending frames or plates 45 and 46, optionally associated with gaskets 47 and 48, said frames or plates being constructed to receive and interfit with hexagonal terminal portions 49 of substantially cylindrical tubes 50,—the ends of said tubes being so sweated or otherwise secured to one another and to said plates or frames as to conduct water from header 42 to header 43, and of such external diameter as to permit 55 60 a flow of oil in thin and repeatedly broken films transversely therebetween. Means such as bolts and/or screws 51, 52 may be employed to hold the mentioned parts in their indicated relationship; and not only the described cooler assembly but also a suitable

water pump W. P., or said pump and/or a suitable fan F may also be supported from the water outlet fittings 44, 44'.

In the present invention, the water inlet header 42 is shown as integral with a water pump chamber casting 53; and this casting is shown as having bolted thereto an additional casting 54, which serves to provide bearings, at 55 and 56, for a fan shaft 57, carrying a pump rotor 58. This may serve for the delivery of cooling water through a passage 59,—which serves not only as an exit from said water pump but as an inlet for the water header 42. The fan shaft 57 may be driven by means such as a usual pulley 60; it may be lubricated through passages, such as are indicated at 61 and 62, in the bearing casting 54; and said shaft or one of said castings should also be provided with a water intake opening 63,—such as that shown as connected with a pipe 64, extending toward the radiator R.

It will be understood that any desired alternative water connections might be provided upon a pump operated by a fan shaft in substantially the described manner, but that the use of hollow bracket or brackets 44, 44' to conduct the water into the respective sides of the engine jacket (preferably via the described heat exchange unit, instead of by a direct return of the water to a water cooling radiator) is highly advantageous in its symmetrical equalization of cooling effects in the engine block. Radiator R may thus be either a sole water-cooling radiator or an auxiliary radiator for the cooling of a fraction or a separate quantity of circulated water to an exceptionally low temperature; but, in case a single water-cooling circuit is provided, radiator R may be connected, as by a usual pipe 66, with the outlet from the jacket of engine block 11,—any desired use of thermostatic devices being, of course, permissible, even though not requisite to the present invention.

The oil cooler O. C. is shown as provided with a cooled oil delivery pipe 67; and the oil advancing therethrough obviously might be conducted directly to the various bearings that require lubrication and/or cooling; or said oil might be delivered to a receptacular element at any preferred elevation and/or pressure. However, in case the delivery pipe 67, shown as connected with the outlet fitting 41, conducts the cool oil back into a pool in the oil pan 12, or its equivalent (in preference to its being so serially connected with a service circuit as to require but one pump) means such as an additional pump O. P.' may be used to advance the oil therefrom into a pressure system,—such as that diagrammatically represented by an additional pipe at 69 and the mentioned camshaft conduit 30. In this case, the intake 70 of the pump O. P.' is preferably so positioned as promptly to receive 100

- the cooled oil,—in advance of any considerable mixture of warm oil therewith. An adjustable relief valve may be provided, as at 71, and the drip of oil therefrom and/or that 5 from the engine bearings will be understood to complete a second or service oil circuit, partially or wholly distinct from the described cooling circuit. In this case oil may be initially admitted to the cooling circuit 10 pump through the drive shaft thereof, as above described, and it will be understood that the normal operation of said pump may soon create such a back pressure therein as substantially to discontinue inflow through said 15 shaft,—the use of any valve (not shown) in said shaft being optional. It will be obvious that the mentioned pumps O. P. and W. P. and also the cooler O. C. are positioned favorably to direct cooling by fan F.
- 20 Although the foregoing description has included complete details of but one embodiment of the present invention, it should be understood not only that various features thereof might be independently employed but 25 also that numerous modifications, additional to those incidentally suggested herein, might easily be devised by lubrication engineers familiar with the foregoing,—all without departure from the scope of the present invention.

I claim:

1. In a water-cooled engine including a block above an oil pan: means for supporting from said block a fan shaft and a camshaft; a cooling water pump and an oil pump respectively driven from said shafts; a water cooled oil cooler interposed between said pumps, and connections between the cooler and the pumps for conducting water and oil 40 to the cooler.
  2. In a water-cooled engine including a block above an oil pan: means for supporting from said block a fan shaft and a camshaft; a cooling water pump and an oil pump respectively driven from said shafts; a water cooled oil cooler interposed between said pumps,—a rotor of one of said pumps being co-axial with one of said shafts, and connections between the cooler and the pumps for conducting water and oil to the cooler.
  3. In a water-cooled engine including a block above an oil pan: means for supporting therefrom a camshaft; and an oil pump driven from said shaft,—said camshaft being provided with a passage which receives oil under pressure; said oil pump being provided with an inlet communication with said passage.
  4. In a water-cooled engine including a block above an oil pan: means for supporting from said block a fan shaft and a camshaft; and a cooling water pump and an oil pump respectively driven from said shafts,—said camshaft being driven by a gear having a
- fixed housing, and one of said pumps being carried by said housing.
5. In a water-cooled engine including a block above an oil pan: means for supporting from said block a fan shaft and a camshaft; a cooling water pump and an oil pump respectively driven from shafts,—one of said shafts being surrounded by a fixed housing which provides one wall of a chamber of the pump driven therethrough.
6. In a water-cooled engine including a block above an oil pan: means for supporting from said block a fan shaft and a camshaft; a cooling water pump and an oil pump respectively driven from said shafts; and a water cooled oil cooler interposed between said pumps,—one of said shafts being terminally surrounded by a fixed housing which provides one wall of a chamber of the pump driven therethrough, one of said pumps being supported from said cooler.
7. In an internal combustion engine comprising a block which provides a jacket for cooling water: a pump for said cooling water; and supporting means for said pump, including a hollow bracket upon said block,—conduits within said bracket being in communication with the interior of said jacket, for a substantially symmetrical advance of cooling water therethrough.
8. In an internal combustion engine comprising a block which provides a jacket for cooling water: a pump for said cooling water; an oil cooler; and supporting means, for said pump and said cooler, including a hollow bracket upon said block,—said cooler being interposed, between said pump and said bracket, in the circuit of said cooling water.
9. In an internal combustion engine comprising a block which provides a jacket for cooling water: an oil cooler; a pump therefor; and a bifurcate bracket, upon said block, providing means for the advance of water through both said cooler and said block.
10. In a lubricating system for an internal combustion engine which includes a block providing a jacket for cooling water, and shaft bearings to be lubricated: an oil cooler; an oil pump; means for advancing cooling water through said jacket and said cooler; an oil cooling circuit which includes said cooler and said oil pump; an oil service circuit which includes said bearings; and means of communication between said circuits through one of said shafts.
11. In a lubricating system for an internal combustion engine which includes a block providing a jacket for cooling water and shaft bearings to be lubricated, an oil pan being disposed therebelow; an oil cooler; means for advancing cooling water therethrough; an oil cooling circuit which includes an oil pump; and an oil service circuit,—said circuits being in communication within said

pan, and also through a passage leading into said oil pump, for a priming effect.

12. In a lubricating system for an internal combustion engine which includes a block and shafts having bearings: an oil cooler; means for advancing cooling water therethrough; and an oil cooling circuit which includes an oil pump,—said oil cooler being mounted upon the front of said block and said pump being adjacent thereto and provided with a rotor which is co-axial with, and driven directly from, a shaft of said engine.

13. In an internal combustion engine which is provided with a cooling fan at one end thereof: a cooling and lubricating system which includes an oil cooler and also a plurality of pumps so positioned as to be cooled by said fan,—one of said pumps being supported by means through which a fluid is advanced.

14. In a liquid cooled internal combustion engine, a cooling liquid pump, a lubricant pump, a lubricant temperature regulator located adjacent to and between the pumps, and connections between the regulator and the pumps for conducting cooling liquid and lubricant to the regulator.

15. In an internal combustion engine, a lubricant sump, a lubricant pump located at a higher level than the sump and adapted to withdraw lubricant therefrom, a lubricant pump located within the sump, and means to prime the first mentioned pump including a passage communicating therewith and with the second mentioned pump.

16. In an internal combustion engine, a lubricant sump, a lubricant temperature regulator, a lubricant pump adapted to withdraw lubricant from the sump, circulate it through the regulator and return it to the sump, and a second lubricant pump having its intake located in the sump adjacent the point at which the first mentioned pump discharges lubricant thereto.

17. In a water cooled internal combustion engine, a lubricant temperature regulator supported from the engine, a water pump mounted on the regulator and connections between the regulator and the pump for conducting water from the pump to the regulator.

18. The invention claimed in claim 17 in which the means for supporting the regulator from the engine constitutes a water passage communicating with the water jacket of the engine.

In testimony whereof I affix my signature.
ROBERT SCHITTKE.
